UNITED STATES PATENT OFFICE.

CLARENCE O. MAPEL, OF CHICAGO, ILLINOIS, ASSIGNOR TO BURROUGHS ADDING MACHINE COMPANY, OF DETROIT, MICHIGAN, A CORPORATION OF MICHIGAN.

ADDING-MACHINE.

No. 893,182.

Specification of Letters Patent.

Patented July 14, 1908.

Application filed July 11, 1905. Serial No. 269,262.

To all whom it may concern:

Be it known that I, CLARENCE O. MAPEL, a citizen of the United States, residing at Chicago, in the county of Cook and State of Illinois, have invented certain new and useful Improvements in Adding-Machines, of which the following is a specification.

My invention relates to what are commonly known as adding or calculating machines, which are adapted to add or accumulate and also to record or print and also list the individual items, such machines being exemplified by the well known Burroughs adding machine, made in substantial accordance with Burroughs's Patents Nos. 504,963 and 505,078, issued on September 12th, 1893.

My invention has application to that type of adding machine which has provision for throwing out or eliminating the adding or accumulating function of the machine, so that the machine is enabled, under certain conditions, or at the will of the operator, to print numbers or amounts without accumulating them and the object of my invention is to provide a machine of this type with means for recording the fact that any particular number or numbers have been printed without accumulation, such result being accomplished by printing a suitable indicating character in connection with such particular number or numbers, with the result that the operator is informed at a glance which numbers or items in the list were accumulated and which were not.

My invention has useful application to a Burroughs machine to which it may be applied as an attachment or an improvement, but it will be understood that my invention is not limited in its application or scope to such machines, but that it may be employed in connection with other machines operating in substantially the same way and used for the same general purposes. For convenience, however, my invention is illustrated as applied to a Burroughs machine and the same will hereinafter be described in connection therewith without limitation thereto.

In the drawings, Figure 1 is an elevation of the left hand side of a Burroughs machine, in which my attachment or improvements have been incorporated; Figs. 2 and 3 detail views illustrating my attachment in connection with well known parts of a Burroughs machine; Fig. 4 a detail view of the means

for depressing or shifting the special type carrier from its normal position to a position to print the total character, and Figs. 5 and 6 illustrations of samples of work of a machine embodying my invention.

60

Inasmuch as the construction and mode of operation of the Burroughs machine is so well known, only those parts concerned with my attachment or improvements need be described. For a more detailed explanation 65 of the Burroughs machine, reference may be had to the Burroughs patents aforesaid.

As is well known, a Burroughs adding machine is provided with a keyboard having a plurality of rows of keys 291 representing 70 different denominations increasing from right to left, each row representing the digits 1 to 9. These keys control a series of stop wires 270 which in turn govern the amount of movement or oscillation of a series of levers or sector bars 611. These levers are hung on a main transverse shaft 600 and are operatively connected at their forward ends with sectors 610, the amount of movement of any lever being dependent upon the value 80 of the particular key operated in the row of keys corresponding to that lever. These levers carry at their rearward ends a series of movable type plates 618, each bearing type representing two digits. After the amount 85 has been set up on the keyboard and upon the actuation of the main operating shaft of the machine, the levers 611 corresponding to the operated rows of keys will be elevated 90 distances corresponding to the keys operated 95 in their respective or corresponding rows of keys, while the levers 611 corresponding to the rows of keys which have not been operated will be permitted to move upwardly a slight distance so as to present the zero 100 type to its hammer. Each of the series of levers, which correspond in number to the number of rows of keys on the keyboard, is provided with hammer mechanism adapted to be driven against any one of the movable 105 type presented to it, with the result that the particular character or type which is presented to the printing line of the platen 1599 will be impressed or printed upon the paper passed around such platen.

The hammer mechanism of a Burroughs machine consists of a series of hammers 715, one for each lever 611, which hammers are pivoted upon a cross shaft 701. Each hammer is provided with a driver 716 having a 110

laterally projecting stud or pin 741, arranged to coöperate with a slot *w* in its hammer. The driver is normally under a tension, by means of the spring 780, to drive its hammer 5 rearwardly against a type plate, but is restrained against such movement by means of a latch 717, there being as many of these latches as there are drivers and hammers. These latches, which are pivoted upon the 10 cross rod or shaft 700 are in turn under the control of a corresponding series of pawls 718 pivoted upon the cross shaft or rod 704. The rearward end of each pawl 718 is spring pressed towards its latch and is arranged to 15 engage the latter unless such rearward end is rocked upwardly by the contact of its forward end against the inclined or cam surface *a* of its lever or sector bar 611. Unless the lever has been operated, such inclined surface 20 will remain presented to its pawl, with the result that the latter will be rocked upwardly and drawn forwardly in the operation of the machine without any effect upon its latch 717, and consequently without effect upon 25 the driver and hammer. When, however, such lever is operated and such cam surface removed from the path of movement of its pawl 718, the latter will be permitted to engage and rock its latch and thereby release 30 its driver and cause its hammer to deliver the blow by reason of the rearward rocking of the stud 741 in the cam *w* of its hammer. It will also be understood, as described in detail in said Burroughs patents, that the latches 35 717 are provided with lugs or tails for transferring the tripping action from left to right, so as to cause printing of ciphers to the right of any digit.

The Burroughs adding machine as now 40 constructed is also provided with means for indicating or recording the fact that a particular amount printed is a total or a subtotal, such machine generally employing a star or asterisk which is printed in connection 45 with and as an incident to the operation of taking a total. This result is accomplished by providing the machine with an extra type carrier or lever and an extra train of hammer mechanism, all arranged at the right hand side 50 of the series of levers or sector bars 611. These parts are under the control of the totalizing mechanism, there being provided a rocking or oscillating arm, moved in the operation of taking a total, for the purpose of controlling 55 the extra pawl of the train of hammer mechanism, such arm being provided with a foot arranged to present to such extra pawl an inclined or cam surface corresponding to that of one of the regular levers, so that the extra 60 hammer is caused to strike the special type on the special type carrier whenever the totalizing mechanism is operated and the rocking arm thereby moved to inoperative position, as respects the extra pawl in the same 65 manner as the inclined or cam surface of the

regular levers are removed from operative position, as respects their pawls. My invention operates in connection with this so-called star attachment of a Burroughs machine with slight changes, for the purpose of 70 accomplishing my particular results, while still retaining the general principles of operation of such star attachment, which *per se*, of course, forms no part of my present invention. This particular construction, modified 75 for present uses, will be hereinafter described after description of the old and well known parts of the Burroughs machine has been completed.

After an amount has been set up on the 80 keyboard and the main shaft of the machine operated, the sectors 610 descend distances corresponding to the value of the keys operated in the rows corresponding thereto, but at the time of the descent of these sectors the 85 series of adding wheel pinions 916 are thrown or rocked out of mesh therewith and remain in that condition until just prior to the ascent or return of the sectors to normal position. This is accomplished in a Burroughs machine 90 in the following manner: The series of adding wheels and their pinions 916 are mounted in a rocking frame having side or end plates 910, which are arranged to rock upon the cross shaft 900, as an axis. This frame is arranged to be 95 operatively connected at the proper time to bring about the desired rocking movements by means of the reciprocating lever or pitman 914, whose forward end is bifurcated and arranged to engage the rocking frame 910 in 100 the usual and well known manner. The rear end of the pitman is pivotally connected with the depending arm of a three-arm lever 913, whose other two arms are provided with laterally extending pins or studs 961 and 105 961*, respectively. This lever 913 is arranged to be oscillated at every operation of the machine, first in an anti-clockwise direction and then in a clockwise direction, with the result that the pitman 914 is reciprocated 110 first forwardly and then rearwardly, the forward movement of the pitman causing a disengagement of the adding wheel pinions from their sectors and the rearward movement permitting the return of such pinions 115 to a position of mesh. This oscillation of the lever 913 is accomplished by the rocking lever 813, which is secured upon the main rock shaft 800, rocked rearwardly upon the forward movement or rocking of the operating 120 handle, if such a handle is employed, and rocked forwardly upon the rearward or return movement of such handle. The operating connection between the levers 813 and 913 is a spring pressed wipe plate 821 pivoted upon the upwardly extending arm of the lever 813 and arranged to coöperate with the studs 961 and 961*. In the rearward or anti-clockwise rocking of the lever 813 the wipe plate 821 contacts the stud 961* and thereby 125 130

rocks the lever 913 in an anti-clockwise direction, Fig. 1, causing the rocking of the adding wheel pinions out of mesh with their sectors. Upon the return or forward rocking of the lever 813, the wipe plate 821 engages the stud 961 and rocks the lever 913 in a clockwise direction, thereby shifting the pitman 914 rearwardly and permitting the return of the adding wheel pinions to a position of mesh in the well known manner.

For the purpose of taking a total at the will of the operator, the pitman 914 is connected with a total key 265, by means of a link 911, so that whenever such total key is depressed 15 the pitman 914 is shifted to a position so that on its forward stroke and the forward stroke of the handle, it will have no effect upon the rocking frame of the adding wheel pinions, which will consequently remain in mesh with 20 their sectors during the forward movement of the operating handle, at which time the sectors descend distances corresponding to the total or accumulation represented by the adding wheels, but such pinions will be removed 25 from mesh with their sectors upon the return movement of the operating handle in case a grand total is taken, with the result that the adding wheels and pinions will be re-set to zero and the machine will be cleared. If, 30 however, a sub-total is to be taken the total key is released at the end of the forward stroke of the operating handle, which operation will permit the adding wheel pinions to remain in mesh with their sectors and the 35 sub-total, which has been rolled off or transferred from the pinions, will be rolled back upon the latter.

In the usual Burroughs machine, the total key is connected with a bell crank 227 whose 40 depending arm is connected by means of a link 226 with a rocking frame having side or end plates 219, carrying between them the usual universal rod or release bar 202, which is concerned in the operation of releasing or 45 re-setting the keys on the keyboard. Whenever the total key is depressed, the pitman 914 is controlled or shifted and at the same time any keys which may have been operated are released.

50 The Burroughs machine as herein shown, Fig. 1, is provided with means for throwing out or eliminating the adding feature or function of the machine, such means, in the present instance, consisting of a swinging or 55 rocking bar or lever 1, which is pivoted at its rearward end upon a fixed stud or pin 2, projecting from the frame of the machine. This bar or lever is operatively connected with a vertically movable stem 3 of a special 60 key 4 at the left hand side of the keyboard and such bar is so positioned as to be projected or depressed into the path of movement of the wipe plate 821, whenever such special key is operated or depressed. The 65 result of this interference with the wipe plate

is the elimination or throwing out of the adding function of the machine, inasmuch as the wipe plate will be caused to return to its normal position without actuating the stud 961, so that the adding wheel pinions 70 which have been thrown out upon the first movement of the machine are left in such condition. These means so eliminating the adding function of the machine do not, *per se*, form a part of my invention.

75 As hereinbefore stated, the usual Burroughs machine is provided with the so called star attachment for the printing of a star or other designating character as an incident to the operation of taking a total, but such attachment is somewhat modified in order to accomplish the purposes of my invention. Referring to Fig. 2, the special type carrier or lever 611^a is pivoted upon the usual fixed plate 723 at the point 723^a and 80 provided with a pin and slot connection therewith. In the present instance, this plate is provided with a transverse slot 723^b to receive the stud or pin 611^b projecting laterally from the extra or special type carrier 85 611^a. This special type carrier is provided with a movable type plate 618^a having two type, the upper one of which, marked 618^b, is the indicating character for the total, the same being, in the present instance, a star, 90 while the other type marked 618^c is the character for indicating the fact that the accumulating function of the machine was eliminated or thrown out at the time any particular item was printed. In the present 95 instance, this latter character is a double cross as shown in the sample of work in Figs. 5 and 6, but as will be understood, any other form of character for the purpose as distinguished from the star character, may be 100 employed.

105 Normally, the indicating character 618^c is presented towards the printing line of the platen, as indicated in Fig. 2, the same being

110 spring pressed to this position, but arranged to be depressed so as to present the star character to the printing line whenever the totalizing mechanism is operated. To this end, the special type character is provided with an arm 5 which extends upwardly just 115 in the rear of the rock shaft 207, which extends between the side plates or frame 219, already described. For the purpose of rocking the arm 5 and thereby depressing the special type carrier 611^a, whenever the totalizing mechanism is operated, the rock shaft 120 is provided with a projection which, in the present instance, is in the form of a bent pin 6, normally bearing against the forward edge of the arm 5 and arranged to rock such arm 125 rearwardly against the tension of the spring 7. One end of this spring is fastened to the arm 5 and the other end to the plate 723, with the result that the special type carrier 130 is held with a yielding pressure, to the nor-

mal position indicated in Fig. 2. Thus, in the act of taking a total, the special type carrier is automatically depressed by the proper setting of the totalizing mechanism, so that the star will be printed in the operation of printing the total and as an incident thereto. It will be understood that the hammer mechanism belonging to the special type carrier is operated in a manner which is well known and it will, therefore, suffice to state that whenever the totalizing mechanism is operated the cross shaft 206 is rocked in an anti-clockwise direction, Fig. 2, with the result that the depending arm 8 which is secured to such rock shaft and provided at its lower end with a foot presenting an inclined or cam surface 8^a, will be swung or rocked upwardly out of the range of the forward end or tail of the special pawl 718^a, whereupon the special latch 717^a, together with the special driver 716^a will be tripped and the special hammer 715^a will be driven against the movable type 618^a.

The special type plate is normally in position to permit printing of the special character 618^a and the special hammer mechanism is caused to operate as an incident to the printing of an amount after the depression of the special key 4, for the purpose of eliminating the adding or accumulating function of the machine. To accomplish this result, I provide an operating connection between the stem of the special key 4 and the rock shaft 206 which is arranged to cause a swinging of the depending arm 8 in the same manner as the depression of the total key, but without causing a rocking of the shaft 207 forming part of the key release mechanism. In the present instance, the usual arm 227¹ which is secured to, and depends from, the shaft 206 on the left hand side of the machine, is provided with a forwardly extending arm 9, whose free end is upturned so as to present its edge to a pin or stud 3^a projecting laterally from the stem 3 of the special key 4. This arm 9 is normally spring pressed against such pin with a yielding pressure, as by means of the spring 10, with the result that the parts now being described are kept in the normal position indicated in Fig. 1. The depending arm 227¹, instead of being pivotally connected with the link 226 as heretofore, so as to move at all times in unison with such link, is arranged to be moved or rocked rearwardly by the link and also to have a movement independent thereof, whenever the special key 4 is operated. For this purpose a stud or pin 250 which projects laterally from the link 226, instead of having a pivotal connection with the depending arm 227¹ is arranged to press against the shoudered end of the latter so as to move the same rearwardly whenever the total key is depressed and to permit the same to move in

that direction whenever the special key 4 is depressed.

It is now evident that whenever the special key 4 is operated the adding function of the machine is thrown out by the projection of the bar or lever 1 into the path of movement of the wipe plate 821 and at the same time through the medium of the arms 9 and 227¹, the depending arm 8 is rocked rearwardly, with the result that when the amount set up on the keyboard is printed the special type 618^a is caused to be imprinted in proximity to such number or amount. In this operation, the special type carrier 611^a remains in its normal position shown in Fig. 2 and it is simply the special hammer mechanism which is put in position to be actuated in the operation of the machine, after the depression of the special key 4. By this means it is possible to employ the machine for the purpose of printing in the same list amounts or items, some of which are accumulated, and some of which are not and to designate by a printed character the item or items which have not been accumulated, so that the operator may tell at a glance at the list the particular items which were simply printed without accumulation and may have a printed record of the fact.

In the operation of taking a total the depending arm 8 is not only moved in the manner and for the purpose already described in connection with the printing of the special designating character, but the special type carrier 611^a is depressed so as to present the star character to the printing line of the platen, as seen in Fig. 3, so that such star will be printed in connection with the total.

According to the present and herein described construction, the machine is capable of printing the total character, that is the star, whenever the totalizing mechanism is set for taking a total and the machine operated, whether the machine is clear or not, with the result that the star alone may be printed, which, if printed at the head of a column or list of items, may be taken as indicating the fact that the machine was clear when that list was started. In like manner, the special character for indicating the non-accumulating condition of the machine may be printed alone, whenever the special key 4 is depressed and the machine operated, the special character thus affording a printed record of the fact that when the machine was operated the accumulating function or mechanism of the machine was thrown out or rendered inoperative, whether an item or number was printed by the machine or not.

An adding machine embodying my invention finds useful application for different classes of accountant work, wherever it is necessary to print in a list or otherwise, that is in the same column or different columns,

amounts or items, some of which are accumulated and some of which are not, my special designating mark indicating and making a record of the fact that the particular item 5 in connection with which it is printed was not accumulated. Such a machine is particularly useful in large stores employing numerous clerks who are known by certain numbers and the record of whose sales are 10 separately printed on sheets with the number of the particular clerk at the head of the list of items representing his sales. It is desirable to employ the adding machine to print the number of the clerk at the head of 15 the list or column, but such number, of course, is one which should not be accumulated. A sample of the work of this particular class is illustrated in Fig. 5, which example shows, by means of the star, that the 20 machine was clear when the list was begun and the number 248, by reason of the double cross mark following, indicates the number of the particular clerk whose sales are listed below, and also indicates the fact that this 25 particular number was not accumulated. As stated, the succeeding items represent the sales made by that particular clerk and the fact that no exponent or indicating characters follow these particular items, indicates that the same were accumulated, the 30 total of the same which is \$10.90, being indicated by the footing, which is followed by the star indicating such total. However, my improved machine may be used for quite 35 different classes of work and for somewhat different purposes. For instance, as shown in the example in Fig. 6, the same may be employed to indicate the fact that any particular number or item of a list of items, 40 whether such particular number occurs at the top or any other place in the list, has not been accumulated or rather has been eliminated from such list. When, as sometimes occurs, the operator discovers that he has set 45 up the wrong amount on the keyboard and makes such discovery after he has started the operating handle forward, it is possible to eliminate such item, so far as accumulation is concerned, by thereupon immediately 50 depressing the special key 4, and completing the operation of the machine, which will result in throwing out the accumulating mechanism and printing the special character adjacent such item. This character thus indicates that this particular item was not accumulated and the operator is thereby relieved 55 of the necessity of passing the complement of the item through the machine in the well known way and of canceling the item, as is usually done by drawing a pencil or pen therethrough. According to the example of 60 Fig. 6, the operator set up on the keyboard the item 4.35, whereas the item should have been 4.55, but, discovering his mistake be-

fore completing the operation of the machine, and before the item has been printed (but after the handle has been started forward, which prevents resetting of the keyboard) the special key has been depressed and the operation of the machine completed, 65 with the result that, while the wrong amount has been printed, it is followed by the special character indicating that the same has not been accumulated in the machine. The operator thereupon sets up the correct 70 amount on the keyboard, which is 4.55 and proceeds with his work.

I claim:

1. In an adding machine, the combination, 80 with the printing and accumulating mechanisms thereof, of mechanism for rendering the accumulating mechanism inoperative, and means for thereby automatically and permanently indicating such fact; substantially as described.

2. In an adding machine, the combination, 85 with the printing and accumulating mechanisms thereof, of mechanism under the control of the operator for rendering the accumulating mechanism inoperative, and means for thereby automatically and permanently indicating such fact; substantially as described.

3. In an adding machine, the combination, 90 with the printing and accumulating mechanisms thereof, of mechanism for rendering the accumulating mechanism inoperative during the operation of printing an item, and means for automatically printing a suitable character to indicate the fact that the accumulating 95 mechanism was rendered inoperative when said item was printed; substantially as described.

4. In an adding machine, the combination, 100 with the printing and accumulating mechanisms thereof, of mechanism for rendering the accumulating mechanism inoperative during the operation of printing an item, and means for printing, in connection with said item and as an incident to the printing thereof, a suitable character to indicate the fact 105 that the accumulating mechanism was rendered inoperative when said item was printed; substantially as described.

5. In an adding machine, the combination, 110 with the printing and accumulating mechanisms thereof, of key-controlled mechanism for rendering the accumulating mechanism inoperative, and means for indicating such fact; substantially as described.

6. In an adding machine, the combination, 115 with the printing and accumulating mechanisms thereof, of means for rendering the accumulating mechanism inoperative, and mechanism controlled by said means for indicating the fact that the accumulating mechanism was so rendered inoperative when any particular item was printed; substantially as described.

7. In an adding machine, the combination, with the printing and accumulating mechanisms thereof, of key-controlled means for rendering the accumulating mechanism inoperative, and mechanism controlled by said means for indicating the fact that the accumulating mechanism was so rendered inoperative when any particular item was printed; substantially as described.
- 10 8. In an adding machine, the combination, with the printing and accumulating mechanisms thereof, of means for rendering the accumulating mechanism inoperative during the operation of printing any particular item, and mechanism controlled by said means for printing a suitable character in connection with such item to indicate such fact; substantially as described.
- 15 9. In an adding machine, the combination, with the printing and accumulating mechanisms thereof, of means under the control of the operator for rendering the accumulating mechanism inoperative, and mechanism operatively connected with said means for indicating the fact that the accumulating mechanism was so rendered inoperative when any particular item was printed; substantially as described.
- 20 10. In an adding machine, the combination, with the printing, accumulating and totalizing mechanisms thereof, of means for rendering the accumulating mechanism inoperative, and mechanism for printing separate designating characters when the totalizing mechanism and said means, respectively, are operated; substantially as described.
- 25 11. In an adding machine, the combination, with the printing, accumulating and totalizing mechanisms thereof, of means for rendering the accumulating mechanism inoperative, and mechanism under the control of the totalizing mechanism and of said means for printing separate designating characters according to whether the totalizing mechanism or said means are operated; substantially as described.
- 30 12. In an adding machine, the combination, with the printing, accumulating and totalizing mechanisms thereof, of means for rendering the accumulating mechanisms inoperative, a special key for operating said means, and mechanism for printing separate designating characters when the totalizing mechanism and said means, respectively, are operated; substantially as described.
- 35 13. In an adding machine, the combination of printing and accumulating mechanism for printing individual items and accumulating and printing the total thereof, means for rendering the accumulating mechanism inoperative, and means for printing with the total a suitable designating character and for printing another suitable designating character in connection with any item printed while the accumulating mechanism was in
- inoperative condition; substantially as described.
- 40 14. In an adding machine, the combination of printing and accumulating mechanisms for printing individual items and accumulating and printing the total thereof, means for rendering the accumulating mechanism inoperative, and means for printing a suitable designating character in connection with and as an incident to the operation of taking a total and for printing another suitable designating character in connection with any item printed while the accumulating mechanism was in inoperative condition; substantially as described.
- 45 15. In an adding machine arranged to print either with or without accumulation, means for automatically and as an incident to the printing without accumulation, printing a suitable character to indicate that a particular item was printed without accumulation; substantially as described.
- 50 16. In an adding machine arranged to print items either with or without accumulation, and to print totals, means for automatically and as an incident to the printing without accumulation, printing a suitable character to indicate that a particular item was printed without accumulation and for also automatically printing another suitable character to distinguish a total from the individual items; substantially as described.
- 55 17. In an adding machine arranged to print either with or without accumulation, special printing mechanism adapted to automatically, and as an incident to the printing without accumulation, print a suitable character to indicate when the machine is in a condition of non-accumulation; substantially as described.
- 60 18. In an adding machine arranged to print items either with or without accumulation and to print totals, special printing mechanism adapted to automatically and as an incident to the printing without accumulation, print a suitable character to indicate when the machine is in a condition of non-accumulation and another suitable character to indicate when the machine is "clear" or when a total is taken; substantially as described.
- 65 19. In an adding machine arranged to print either with or without accumulation, the combination with the printing, accumulating and totalizing mechanisms thereof, of means for rendering the machine non-accumulating, and a special printing mechanism under the control separately of said means and said totalizing mechanism for printing separate designating characters to indicate the fact of non-accumulation and the fact of the taking of a total; substantially as described.
- 70 20. In an adding machine arranged to print either with or without accumulation

- the combination with the printing, accumulating and totalizing mechanisms thereof, of means for rendering the machine non-accumulating, special keys for operating 5 said means and the totalizing mechanism, and a special printing mechanism under the control separately of said means and said totalizing mechanism for printing separate designating characters to indicate the fact of 10 non-accumulation and the fact of the taking of a total; substantially as described.
21. In an adding machine, the combination, of printing, and accumulating mechanisms, means for rendering the machine non- 15 accumulating, and a special printing device comprising a type carrier having a type character to indicate the condition of non-accumulation of the machine, and hammer mechanism for said type carrier adapted to 20 automatically produce an imprint from the latter's type as an incident to a non-accumulating operation of the machine.
22. In an adding machine, the combination, of printing and accumulating mechanisms, means for rendering the machine non- 25 accumulating, and a special printing device comprising a type carrier having a type character to indicate the condition of non-accumulation of the machine, a hammer for 30 forcing the type of said carrier against the platen, a latch normally restraining said hammer from movement, and a trip for said latch, under the control of said means; substantially as described.
- 35 23. In an adding machine, the combination, of printing, and accumulating mechanisms, means for rendering the machine non-accumulating, and a special printing device comprising a type carrier having a type character 40 to indicate the condition of non-accumulation of the machine, a hammer for forcing the type of said carrier against the platen, a latch normally restraining said hammer from movement, a trip for said 45 latch, and operating connections between said means and the trip for controlling the latter; substantially as described.
24. In an adding machine, the combination, of printing, and accumulating mechanisms, means for rendering the machine non- 50 accumulating at the will of the operator, and a special printing device comprising a type carrier having a type character to indicate the condition of non-accumulation of the machine, and hammer mechanism arranged to 55 strike the type and under the control of said means; substantially as described.
25. In an adding machine, the combination, of printing, accumulating and totalizing 60 mechanisms, means for rendering the machine non-accumulating, and a special printing device co-operating with said means and said totalizing mechanism and arranged to print suitable characters designating a total 65 or the fact of non-accumulation, said print-

ing device being normally in position to print the character to designate the fact of non-accumulation; substantially as described.

26. In an adding machine, the combination of printing, accumulating and totalizing mechanisms, means for rendering the machine non-accumulating, a special printing device comprising a movable type carrier having a type plate with two type representing distinguishing characters to respectively 75 designate a total and the fact of non-accumulation, said carrier being normally in position to print the last named character, hammer mechanism, an arm arranged to control the latter, an operating connection between 80 the totalizing mechanism and said arm and type carrier to shift the latter to position to print the total character and to set the hammer mechanism in position for tripping, and an operating connection between said means 85 and said arm; substantially as described.

27. In an adding machine, the combination of printing, accumulating and totalizing mechanisms, means for rendering the machine non-accumulating, a special printing 90 device comprising a movable type carrier having a type plate with two type representing distinguishing characters to respectively designate a total and the fact of non-accumulation, said carrier being normally in position to print the last named character, hammer mechanism, an arm arranged to control the latter, and moved in every operation of the totalizing mechanism, a rock shaft operatively connected with the totalizing mechanism and arranged to shift the type carrier 95 to a position to print the total character, and an operating connection between said means and said arm; substantially as described.

28. In an adding machine, the combination of printing, accumulating and totalizing mechanisms, means for rendering the machine non-accumulating, a special printing device comprising a movable type carrier having a type plate with two type representing distinguishing characters to respectively 100 designate a total and the fact of non-accumulation, said carrier being normally in position to print the last named character, hammer mechanism, an arm arranged to control the latter, an operating connection between 105 the totalizing mechanism and said arm and type carrier for shifting both of them at every operation of the totalizing mechanism, the type carrier being thereby shifted to print 110 the total character, and an operating connection between said means and said arm for shifting the latter without shifting the type carrier; substantially as described.

29. In an adding machine, the combination of printing, accumulating and totalizing mechanisms, means for rendering the machine non-accumulating, a special printing device comprising a movable type carrier having a type plate with two type represent- 115

- ing distinguishing characters to respectively 5 designate a total and the fact of non-accumulation, said carrier being normally in position to print the last named character, hammer mechanism, an arm arranged to control the latter and moved in every operation of the totalizing mechanism, an arm connected with the type carrier for shifting the latter to a position to print the total character, an operating connection between the totalizing mechanism and both of said arms, and an operating connection between said means and the first named arm; substantially as described.

10 30. In an adding machine, the combination of printing, accumulating and totalizing mechanism, means for rendering the machine non-accumulating, a special printing device comprising a movable type carrier having a type plate with two type representing distinguishing characters to respectively designate a total and the fact of non-accumulation, said carrier being normally in position to print the last named character, hammer mechanism, an arm arranged to control the latter, and moved in every operation of the totalizing mechanism, an arm connected with the type carrier for shifting the latter to a position to print the total character, a rock shaft arranged to actuate the arm of the type carrier, an operating connection between the totalizing mechanism and the rock shaft and also with the arm controlling the hammer mechanism, and an operating connection between said means and the last mentioned arm; substantially as described.

15 31. In an adding machine, the combination of printing, accumulating and totalizing mechanisms, means for rendering the machine non-accumulating, a special printing device comprising a movable type carrier having a type plate with two type representing distinguishing characters to respectively designate a total and the fact of non-accumulation, said carrier being normally in position to print the last named character, hammer mechanism, an arm arranged to control the latter and moved in every operation of the totalizing mechanism, an arm connected with the type carrier for shifting the latter to a position to print the total character, a rock shaft arranged to actuate the arm of the type carrier, a second rock shaft on which the other arm is mounted, an operating connection between the totalizing mechanism and the rock shafts, said second rock shaft having a movement independent of the first rock shaft, and a key operatively connected with said means and with the second rock shaft to operate said means to throw out the accumulating function of the machine and to rock the second shaft to place the hammer mechanism in position to be tripped in the operation of the machine; substantially as described.

20 32. In an adding machine, the combination of printing, accumulating and totalizing mechanisms, means for rendering the machine non-accumulating, a special printing device comprising a movable type carrier having a type plate with two type representing distinguishing characters to respectively designate a total and the fact of non-accumulation, said carrier being normally in position to print the last named character, hammer mechanism, an arm arranged to control the latter, and moved in every operation of the totalizing mechanism, an arm connected with the type carrier for shifting the latter to a position to print the total character, a rock shaft arranged to actuate the arm of the type carrier, a second rock shaft on which the other

25 33. In an adding machine, the combination of printing, accumulating and totalizing mechanisms, means for rendering the machine non-accumulating, a special printing device comprising a movable type carrier having a type plate with two type representing distinguishing characters to respectively designate a total and the fact of non-accumulation, said carrier being normally in position to print the last named character, hammer mechanism, an arm arranged to control the latter, and moved in every operation of the totalizing mechanism, an arm connected with the type carrier for shifting the latter to a position to print the total character, a rock shaft arranged to actuate the arm of the type carrier, a second rock shaft on which the other arm is mounted, an operating connection between the totalizing mechanism and the rock shafts, said second rock shaft having a movement independent of the first rock shaft, and a key operatively connected with said means and with the second rock shaft to operate said means to throw out the accumulating function of the machine and to rock the second shaft to place the hammer mechanism in position to be tripped in the operation of the machine; substantially as described.

30 34. In an adding machine, the combination of printing, accumulating and totalizing mechanisms, means for rendering the machine non-accumulating, a special printing device comprising a movable type carrier having a type plate with two type representing distinguishing characters to respectively designate a total and the fact of non-accumulation, said carrier being normally in position to print the last named character, hammer mechanism, an arm arranged to control the latter, and moved in every operation of the totalizing mechanism, an arm connected with the type carrier for shifting the latter to a position to print the total character, a rock shaft arranged to actuate the arm of the type carrier, a second rock shaft on which the other

arm is mounted, an operating connection between the totalizing mechanism and the rock shafts, said second rock shaft having a movement independent of the first rock shaft, 5 a bell crank on the second shaft, and a special key having a stem operatively connected with said means to throw out the accumulation of the machine and operatively connected with said bell crank; substantially as 10 described.

35. In an adding machine, the combination of printing, accumulating and totalizing mechanisms, means for rendering the machine non-accumulating, a special printing device comprising a movable type carrier having a type plate with two type representing distinguishing characters to respectively designate a total and the fact of non-accumulation, said carrier being normally in position to print the last named character, hammer mechanism, an arm arranged to control the latter and moved in every operation of the totalizing mechanism, an arm connected with the type carrier for shifting the latter to 20 a position to print the total character, a rock shaft arranged to actuate the arm of the type carrier, a second rock shaft on which the other arm is mounted, crank arms on said shafts, link connections between the totalizing mechanism and both crank arms, the arm of the second shaft having a movement independent of such connections, and a special key having a stem operatively connected with said means and with the crank arm of 30 the second shaft; substantially as described.

36. In a machine of the character described, the combination with means for printing individual items *seriatim*, and means for accumulating the total of printed 40 amounts; of means for disabling the accumulating means at will with provisions for automatically and as an incident to disablement of accumulating means, characterizing the imprint of an unaccumulated amount.

45. 37. In an adding and listing machine, the combination of printing devices including a special printer, an accumulator cooperating with the printing devices, actuators for the accumulator, devices for regulating the periods of engagement between the latter and the actuators according as a total is to be printed or an item printed and accumulated, and means coöperating with such regulating devices to prevent accumulation while permitting the printing of an item, with provisions for causing the special printer to act and designate such item as an unaccumulated one.

38. In an adding and listing machine, the combination of printing devices, an accumulator coöperating with the printing devices, actuators for the accumulator, devices

for regulating the periods of engagement between the latter and the actuators according as a total is to be printed or an item printed and accumulated, means for printing a designating character in association with a printed total, and means coöperating with the regulating devices to prevent accumulation while permitting the printing of an item, with provisions for printing a special designation with such item to distinguish it from totals and accumulated items. 65

39. In an adding and listing machine, the combination of printing mechanism including a special type carrier and impression means normally restrained, an accumulator coöperating with the printing mechanism, actuators for the accumulator, devices for regulating the periods of engagement between the latter and the actuators according as a total is to be printed or items printed and accumulated, and means coöperating with said regulating devices to prevent accumulation, and acting to release the impression means for the special type causing the latter to print a character with the item for distinguishing it from accumulated items. 75

40. In an adding and listing machine, the combination of printing mechanism including a special type carrier and impression means normally restrained, an accumulator coöperating with the printing mechanism, actuators for the accumulator, devices for regulating the periods of engagement between the latter and the actuators according as a total is to be printed or items printed and accumulated, means for automatically setting the special type carrier and releasing its impression means when the regulating devices are adjusted to cause the printing of a total, and means coöperating with said regulating devices to prevent accumulation of a printed item and acting to release the special impression means and cause a character to be printed with such item distinguishing it from accumulated items and from totals. 95

41. In a machine of the class described, accumulating mechanism, printing mechanism, means for simultaneously operating both of said mechanisms and means for interrupting the operation of the accumulating mechanism, in combination with means for, automatically and as an incident of said interruption, causing items printed during said interruption to be recorded in a manner distinguishing them from those printed at other times. 100 110 115
